OAR OPERATING MECHANISM

Conrad Carlson, Brooklyn, N. Y.

Application December 8, 1937, Serial No. 178,631

9 Claims. (Cl. 9—25)

This invention relates to rowing units of the kind disclosed in Letters Patent of the United States No. 2,058,410, granted to me on October 27, 1936, and is in the nature of an improvement upon the invention disclosed and claimed in said patent.

In common with my said patented invention the present invention is designed to provide a form of mechanism which permits the rower of a boat to face forward when propelling the boat.

In the mechanism illustrated in my patent, a longitudinal shaft is clamped at spaced points fore and aft to each gunwale of the boat and a sleeve is rotatably mounted on the shaft. Bearing clamps are affixed to the sleeve to provide parallel pivot bearings rockable in unison with the sleeve. An oar is clamped to one of the bearings and an operating lever to the other, and a link disposed to cross the line of pivots is pivotally connected to the oar at the outboard side of the line of pivots and to the operating lever at the inboard side of the line of pivots. As a result of this arrangement, the rise and dip of the oar is controlled from the operating lever just the same as it would be from a normal oar handle, but motion of the operating lever toward the front of the boat causes the oar blade to move toward the front of the boat, and movement of the operating handle toward the rear causes the oar blade to move toward the rear, the relation being just the reverse of that which occurs when an ordinary oar is operated by its handle.

These principles are in general adhered to in the practice of the present invention. The present invention, however, embodies a number of advantageous features of improvement over the prior construction.

In the prior construction, the sleeve which carries the pivot brackets for the oar and for the operating lever has extensive bearing engagement with the stationary shaft upon which it is rotatably mounted, and since the space between the tube and the shaft is exposed to dirt and water, considerable friction and wear are apt to develop.

In accordance with an important feature of the present invention, the gunwale clamps form direct bearings for a rock shaft and the pivot brackets for the oar and for the operating lever are secured directly to the forward and rearward extremities of the shaft, respectively. The shaft is thus provided with short but adequate bearings near its ends, the bearings being located closely adjacent to the points at which the

shaft is connected to the oar and to the operating handle.

In the prior construction the oar is secured by independent clamps to the rock shaft and to an operating link, there being nothing other than trial and error to guide the user in determining how far apart the two clamps should be set upon the oar, and no way of maintaining the desired spacing when the oar is removed.

In accordance with the present invention, an oar supporting arm is formed with two clamps, one adjacent the oar pivot and the other adjacent the point of connection with the operating link, these clamps being positively and definitely connected to one another in fixed spaced relation.

A further feature of the invention has to do with the provision on the oar supporting arm of clamp adjusting means for enabling the clamp to cooperate properly and effectively with oars of different diameters and of different degrees of taper. By making the two halves of the oar clamp bodily adjustable toward one another, a proper adjustment can be secured in advance of the application of clamping pressure which will enable the clamp to act most effectively and with a minimum of mutilation upon the oar.

A further feature of the present invention has to do with an arrangement of the parts of the rowing unit in such manner that the parts can be conveniently folded into a compact, fixed form, upon being detached from the oar and the boat, without disturbing the relation of any of the parts of the unit which are clamped to one another in use. As a result of this feature, the unit can be readily removed from the boat and the oar for convenient transportation and can be re-applied at a subsequent time without the necessity of any tinkering or experimenting, and with absolute assurance that it will operate in exactly the same way in which it operated before.

Other objects and advantages will hereinafter appear.

In the drawings forming part of this specification, and illustrating certain practical and advantageous embodiments of the invention:

Fig. 1 is a fragmentary, plan view illustrating the right hand or starboard side of a row boat having a rowing unit embodying features of the present invention applied thereto;

Fig. 2 is a detail view in end elevation of the rear gunwale clamp, the operating lever supporting bracket, and associated parts;

Fig. 3 is a detail, sectional view taken on the line 3—3 of Fig. 1, looking in the direction of the arrows;

Fig. 4 is a detail, sectional view taken on the line 4-4 of Fig. 1, looking in the direction of the arrows;

Fig. 5 shows one way of collapsing the rowing unit when the oar has been detached therefrom, and after it has been removed from the boat to enable it to be conveniently transported;

Fig. 6 is a fragmentary top plan view showing the oar clamps open; and

Fig. 7 is a side elevation of a detached rowing unit of modified construction which has been collapsed for transportation in a manner different from that illustrated in Fig. 5.

The rowing unit of Figs. 1 to 6 is disclosed in Fig. 1 as applied to a row boat 1. Clamps 2 and 3 are applied fore and aft to the right hand or starboard gunwale of the boat. Each clamp comprises a hook 4 having a clamping jaw 5 and a threaded shank or stem 6. The stem 6 passes freely through a clamping member 7, which includes a clamping jaw 8. A wing nut 9, threaded on the stem 6 and engaging the clamping member 7, is utilized for applying clamping pressure to draw the jaws 5 and 8 towards one another when they have been placed at opposite sides of the gunwale. Each clamping member 7 is formed with a bore 10 for receiving a tubular shaft 11. The shaft 11 has pins 12 and 13 fast upon it for cooperating with the clamping members 7, to determine the correct spacing between the clamps 2 and 3 when applying the rowing unit to the boat and for opposing longitudinal play of the shaft 11 when the clamps have been applied to the boat.

The shaft 11 bears in the bores 10 of the clamping members 7 and is rockable therein.

Upon the rear end of the shaft 11, a bearing bracket 14 is mounted, the bracket being in the form of a sleeve with a circular boss 15 projecting upward from the upper side thereof. The boss 15 is formed with an axially extending threaded bore for receiving a pivot bolt 16 which functions both as a pivot bearing and as a set screw for fixing the position of the bracket or sleeve 14 upon the shaft 11, and for constraining the bracket or sleeve 14 to turn in unison with the shaft 11. An operating lever clamp 17 comprises a bearing portion 18 which is journaled upon the pivot bolt 16. The clamp 17 also comprises a split ring 19, Fig. 2, having ears 20 and 21. The ring 19 is clamped firmly to the fulcrum end of an operating lever 22 by means of a screw bolt 23 passed through the ears, and a nut 24 threaded on the bolt.

At the forward end of the shaft 11, an oar supporting bracket 14 is mounted, this bracket being the same in construction as the rear bracket 14, and being held to the shaft 11 by a pivot bolt 16 in the same manner that the rear bracket is held to the shaft. An oar clamping arm 25 is pivotally mounted upon the forward pivot bolt 16 by means of a bearing sleeve 26 integral with the arm 25. The arm 25 is adapted to project in operation for a considerable distance outward from the gunwale of the boat and is provided with inner and outer oar clamps 27 and 28. The inner oar clamp 27 comprises substantially semi-circular clamping members 29 and 30, Figs. 1 and 3, the former being integral with the arm 25. The clamping member 30 is formed with ears 31 between which a threaded link 32 is pivotally mounted by means of a bearing pin 33 which is fixed in the ears and passes freely through the link. The threaded end of the link 32 is screwed into an ear 34 which is integral with the clamping

member 29. The clamping members 29 and 30 are desirably lined with deformable liners 35, which may be glued thereon, said liners being composed of a yieldable friction material, such as leather, rubber, etc.

With the clamping members connected to one another as described, it is evident that the clamping member 30 can be swung toward and from the clamping member 29 by turning it about the pivot 33. The clamping member 29 is also provided with ears 36, Figs. 5 and 6, between which a threaded link 37 is pivotally mounted by means of a pivot pin 38. The link 37 is adapted to be passed freely through a slotted ear 39 integral with the clamping member 39. A wing nut 40 is threaded onto the link 37 and is utilized for forcing the clamping member 30 toward the clamping member 29 to apply clamping pressure to an oar 41.

The clamp 22 is desirably similar in all respects to the clamp 27 so that no detailed description of the clamp 22 is deemed necessary.

With the clamp construction described, either clamp can be preliminarily adjusted by withdrawing the link 37 from the slot of the ear 39, and then turning the link 32 to adjust the pivot pin 33 toward or from the clamping member 29 as desired. Most desirably, an adjusted position is chosen which will cause the juxtaposed plane faces of the clamping members 29 and 39 to stand substantially parallel to one another when the parts have been brought together to clamp an oar firmly between them. The clamp 28 will generally clamp a smaller portion of the oar than is clamped by the clamp 27, and hence the pivot 33 of the clamp 28 will be initially set closer to the clamping member 29 of the clamp 27, than the pivot 33 of the clamp 27 is set to the clamping member 29 of the clamp 27.

The operating lever 22 is connected to the oar 41 through an operating link 42. The clamp 43 for connecting the link to the operating lever 22 is like the clamp 17 which has already been described. That is to say, the clamp comprises a bearing member 44, a split ring 45, and ears 46 disposed in opposed relation. The ears 46 are drawn toward one another by means of a screw or bolt 47 and a nut (not shown).

The link 42 is formed with downturned ends 48 and 49. The end 48 is passed through the bearing member 44 of the clamp 43 and is secured against separation from the clamp by any suitable means, such as a cross pin 49 driven through the lower extremity of the end 48. The downturned end 49 of the link 42 passes downward through a bearing member 50 which is integral with the arm 25.

It will be observed that the link 42 crosses the plane of the pivot bolts 16, and hence that the outer end or blade of the oar will always move fore and aft, respectively, as the operating lever is moved fore and aft. Depression of the operating lever will rock the shaft 11 to raise the oar blade, while raising of the operating lever 22 will rock the shaft 11 to lower the oar blade.

When it is desired to remove the rowing unit from the boat, the oar may be readily removed from the unit by backing off the wing nuts 40 to unclamp the oar. No other parts of the unit which have been clamped in proper, relatively adjusted positions, need to be disturbed. The clamps 2 and 3 are simply unclamped from the gunwale and the parts then come off as a unit.

In the form illustrated in Figs. 1 to 6, this unit can be conveniently collapsed and fixed in col-

lapsed position for transportation in the manner illustrated in Fig. 5. This consists of lifting the end 49 of the operating link 42 out of the bearing member 50, swinging arm 25 to the rear, placing the link 42 and the operating lever 22 through the clamp 23, while in open position in Fig. 6, then closing the clamp 23 and placing the operating link through the clamp 27, and then closing the latter, both clamps being closed by means of 10 their wing nuts 48.

The rowing unit for the left hand side of the boat is similar in all respects to the rowing unit for the right hand side, with the obvious exception that it is set up as a left hand part rather than a 15 right hand part. This exception, however, does not necessitate the making of any individual part different in any way from the corresponding part of the right hand unit. All four of the clamps 2 and 3 may be identical. All four of the brackets 20 14 may be identical. The two shafts 11 may be identical. The two clamps 17 and the two clamps 43 may be identical with one another. The arms 25 with their associated clamps may also be identical. At the left hand side of the boat, however, 25 the bearing member 50 would be used in association with the pivot bolt 16 and the bearing member 26 would be used in conjunction with the forward end of the left hand operating link 42. The arm 25 is made symmetrical with respect to its 30 middle to enable it to be thus selectively used.

The only difference between the embodiment of Fig. 7 and the embodiment of Figs. 1 to 6, consists in the fact that a longer operating lever 22a is employed, and in the fact that the clamp 43a is secured to the operating lever at a point 35 farther out from the operating lever pivot than the point of securing of the clamp 43 to the operating lever 22.

Since the parts are otherwise identical, no 40 detailed description will be given of the Fig. 7 construction, but corresponding reference numerals have been applied to corresponding parts with the subscript *a* added.

The point of connection of the clamp 43a to 45 the operating lever 22a is so chosen that the arm 25a can be swung forward to a position substantially in alignment with the shaft 11a without disconnecting the link 42a from the clamp 43a or from the arm 25a. With this arrangement 50 the parts can be swung to a condition like that shown in Fig. 7. In this position the operating lever 22a is passed into the clamp 27a and the clamp is then closed upon the operating lever. This secures all of the parts against objectionable 55 relative movement so that the unit can be conveniently carried or packed.

I have described what I believe to be the best 60 embodiments of my invention. I do not wish, however, to be confined to the embodiments shown, but what I desire to cover by Letters Patent is set forth in the appended claims.

I claim:

1. In a rowing unit in combination, a rigid 65 oar carrying arm comprising a connecting member, semi-circular clamping members integrally connected to the ends of said connecting member, each of said clamping members having an integrally formed bearing sleeve secured thereto, said bearing sleeves being disposed in substantial 70 alignment and on the same side of said connecting member, a pair of clamp jaws adapted to clamp the oar against said clamping members, means for pivotally supporting one of said bearing sleeves for oscillation about both a horizontal axis and a vertical axis, and means for oper- 75

ating the arm to and fro comprising an operating link having an end portion pivotally connected to the other of said bearing sleeves.

2. In an oar operating unit, in combination, 53 an operating lever, a pair of gunwale clamps, a shaft pivotally mounted in the clamps, and abutment means on the shaft for limiting the approach of the clamps toward one another and controlling the spacing of the clamps for application to the gunwale. 10

3. In an oar operating unit, in combination, 15 an operating lever, a pair of gunwale clamps, a shaft pivotally mounted in the clamps, abutment means on the shaft for limiting the approach of the clamps toward one another and controlling the spacing of the clamps for application to the gunwale, an operating lever bracket fixed to the shaft at the rear side of the rear clamp, and an oar carrying bracket fixed to the shaft 20 at the forward side of the forward clamp. 20

4. In an oar operating unit, in combination, an operating lever, a shaft, means securing the shaft upon a gunwale with capacity for rocking movement about a fore and aft extending axis, an operating lever bracket impaled on said shaft, an operating lever clamp pivotally mounted on the bracket, and a pivot bolt passed through the clamp and threaded into the bracket to provide a bearing for the clamp, said pivot bolt being threaded firmly against the shaft to fix the bracket against longitudinal and rotative movements relative to the shaft. 25

5. In an oar operating unit, in combination, 35 an operating lever, a shaft, means securing the shaft upon a gunwale with capacity for rocking movement about a fore and aft extending axis, an oar supporting bracket impaled on the shaft, an oar clamping member pivotally mounted on the bracket, and a pivot bolt passed through the 40 clamp and threaded into the bracket to provide a bearing for the clamping member, said pivot bolt being threaded into firm engagement with the shaft to fix the bracket against longitudinal and rotative movements relative to the shaft. 40

6. In an oar operating unit, in combination, 45 a shaft, a pair of bearing clamps rotatively supporting the shaft and fixed longitudinally thereof, an operating lever, means mounting the operating lever on the shaft for rotation with the shaft and about an axis transverse to the shaft, an oar 50 supporting arm including a pair of oar clamps, means mounting the arm on the shaft for rotation with the shaft and about an axis transverse to the shaft, and an operating link for connecting the operating lever with the oar supporting arm, said link being detachably connected to the oar supporting arm, and said link, lever and arm being all swingable when the link is detached 55 from the arm to align the lever and link with the arm for securing the arm thereto. 60

7. In an oar operating unit, in combination, 65 a shaft, a pair of bearing clamps rotatively supporting the shaft and fixed longitudinally thereof, an operating lever, means mounting the operating lever on the shaft for rotation with the shaft and about an axis transverse to the shaft, an oar supporting arm including a pair of oar clamps, means mounting the arm on the shaft for rotation with the shaft and about an axis 70 transverse to the shaft and an operating link for connecting the operating lever with the oar supporting arm, said arm being swingable into position to align the arm substantially with the shaft, and said lever being movable into one of the 75

clamps of said arm for packing or transportation.

8. In an oar operating unit in combination, a shaft, an operative lever and an oar clamping arm pivotally mounted at a fixed distance from one another on the shaft and an operating link for operatively connecting the lever and arm, said lever and arm being constructed and arranged to be aligned and rigidly interconnected for packing and transportation.

9. A pair of oar operating units for use, respectively, upon the right and left sides of a rowboat, each unit including a shaft, spaced

apart bearing clamps pivotally supporting the shaft, an operating lever, an oar carrying arm having a pair of spaced apart supporting brackets disposed in a plane substantially parallel to the axis of the oar and said brackets having similar, vertically disposed journal bearings, a supporting bracket for the operating lever, operating lever clamps, and an operating link, all of said parts being so constructed and arranged that they can be used interchangeably in the right hand unit and in the left hand unit. 10

CONRAD CARLSON.
